UNITED STATES PATENT OFFICE.

ELIJAH R. VAN ALLEN, OF NORTH TONAWANDA, NEW YORK.

SAFETY DEVICE FOR ELEVATORS.

SPECIFICATION forming part of Letters Patent No. 684,560, dated October 15, 1901.

Application filed January 18, 1901. Serial No. 43,698. (No model.)

To all whom it may concern:

Be it known that I, ELIJAH R. VAN ALLEN, a citizen of the United States, residing at North Tonawanda, in the county of Niagara 5 and State of New York, have invented certain new and useful Improvements in Safety Devices for Elevators, of which the following is a specification.

My invention relates to an improved safety device for elevators, in which a lock for stopping the descent of the car is automatically thrown into operating position by the breaking of the cable; and the object of the invention is to construct a simple, cheap, and positive device of this character.

For a full understanding of the merits and advantages of the invention, reference is to be had to the accompanying drawings and the following description.

The invention is susceptible to various changes in the form, proportion, and minor details of construction without departing from the principle or sacrificing any of the advantages thereof; and to a full disclosure of the 25 invention an adaptation thereof is shown in the accompanying drawings, in which—

Figure 1 is a side elevation of a car and a portion of an elevator equipped with my improved safety device. Fig. 2 is an end elevation of a car and a portion of an elevator equipped with my improved safety device. Fig. 3 is an enlarged vertical section on line *a a*, Fig. 4. Fig. 4 is an enlarged horizontal section on line *b b*, Fig. 3. Fig. 5 is an enlarged vertical section on line *c c*, Fig. 3. Fig. 6 is an enlarged detached view of one of the end plates. Fig. 7 is an enlarged detached view of one of the locking-plates. Fig. 8 is an enlarged end view of one of the end plates.

In referring to the drawings in detail like numerals designate like parts.

The elevator-car shown in the drawings is composed of a platform 1, two vertical side supports 2, each of which extends upward 45 from substantially the center of one of the sides of the platform, a horizontal top support 3, formed of two parallel boards slightly separated from each other, and two end plates 4, each formed substantially as shown in Fig. 5, which are bolted to the upper ends of the vertical supports 2 by the bolts 5 and provided with sockets in which the ends of the

board of the top support 3 are firmly seated. The end plates 4 are each provided with two curved lugs 7 and a slot 8, which extends at 55 an angle to the sides of the plate. The locking mechanism consists of two levers provided with friction locking-shoes, which contact with the guide-post and instantly stop the motion of the car upon the breaking of 60 the cable.

For a detail description of the specific adaptation of the locking mechanism shown in the drawings reference is to be had particularly to Figs. 3, 4, 5, 6, and 7. Two levers 9, preferably consisting of flat metal strips, are arranged between the two parallel boards forming the top support, with their inner ends slightly lapping each other. (See Fig. 4.) Top and bottom plates 10 and 11 are 70 bolted to the upper and lower surfaces of substantially the center of the top support and are provided with openings 12 and 13 for the passage of a vertical flat pin 14. This pin passes between the lapping ends of the levers 9 and has an eye 15 at its upper end for the attachment of the cable 16, which supports the car, and an enlarged head 17 at its lower end, upon which a plate 18 is supported. A pintle 19 passes through the lapping ends 80 of the lever and the body portion of the vertical flat pin 14 and serves to pivotally fasten these three parts together. (See Fig. 4.) The levers extend in opposite directions, and the outer end of each lever passes through one 85 of the inclined slots 8, and a locking device in the form of a plate 20, having one roughened or serrated edge 21, is rigidly fastened to the outer end of each lever. Each lever is pivoted to the top support 3 by a pin 22, 90 which passes through the two parallel boards comprising the top support and the lever. A box or case 23 is bolted to each side of the top support and contains a spiral spring 24, which bears against the plate 18.

The operation of the device is as follows: The car is arranged with lugs 7 projecting each side of the vertical guide-posts 25, and one of the plates 20 with its roughened or serrated edge 21 slightly out of contact with one 100 side of one of the guide-posts and the other plate with its roughened or serrated edge slightly out of contact with the opposite side of the remaining guide-post. Now the weight

of the car holds the pin 14, attached to the cable 16, in an elevated position against the tension of the springs 24, so that when the cable breaks the pin is instantly released and drawn downward by the springs. This movement of the pin turns the levers on the pivot-pins 22 and brings the serrated edges 21 of the plates 20 into contact with the side surface of the guide-posts 25. As the slots 8 extend at an angle to and upward and inward toward the guide-posts, the downward movement serves to force the plates 20 into tighter contact, and thus assists in locking the car.

The principal advantages of the invention are the certain and almost instantaneous automatic action of the safety device, the fact that it cannot be prevented from locking by the swelling or shrinking of the boards or the rusting of the metal portions, and that it will catch and hold the car when loaded to its fullest capacity without injuring the guide-posts or the working parts of the safety device.

To assist the levers and render the action of the device more perfect, an inclined lug 27 can be arranged to extend from each end plate on one side of the diagonal slot 8 to form a wedging device, and the lock-plates can each be provided with an inclined edge 28, adapted to slide on the surface of the lug 27, and thus wedge themselves into locking position by the downward movement of the car. This will practically release the outer ends of the levers from strain when the device is operating to lock the car.

I claim as my invention--

1. The combination with the guide-posts and car having a top beam formed of two separated pieces and slotted end plates, of a safety device comprising levers supported between the pieces of the top beam and projecting through the slots in the end plates, and gripping devices carried by the levers and adapted to grip the guide-posts.
2. The combination with the guide-posts, the car having a two-piece top beam, and the supporting-cable, of a safety device comprising levers supported between the two pieces of the beam and plates engaged by said levers adapted to grip the guide-posts, a flat pin having its lower end extending between and connected to the inner ends of the levers and its upper end connected to the car-supporting cable, and means for automatically moving the levers to bring the plates into

gripping contact with the guide-posts upon the breaking of the supporting-cable.

3. The combination with the guide-posts, the supporting-cable, and car, of end plates having slots extending at an angle to the 60 guide-posts, levers connected to the supporting-cable and extending through the slots, and lock-plates attached to the levers.

4. The combination with the guide-posts, the supporting-cable and car, of end plates 65 having slots extending upward and inward toward the guide-posts, levers connected to the supporting-cable, and extending through the slots and lock-plates at the outer end of the levers.

5. In an elevator, guide-posts, a car having a top beam formed of two parallel pieces, end plates having inclined slots, two levers pivoted between the parallel pieces with their outer ends extending through the inclined 75 slots, lock-plates fastened to the outer ends of the levers, a pin connected to the inner ends of the levers, and a supporting-cable connected to said pin, as set forth.

6. In an elevator, guide-posts, a car having 80 a top beam formed of two parallel pieces, end plates having sockets in which said pieces are seated, holding-lugs and diagonally-extending slots, two levers pivoted between the parallel pieces with their outer ends extending 85 through the diagonally-extending slots, lock-plates fastened to the outer ends of the levers, a pin connected to the inner ends of the levers, a supporting-cable connected to said pin, a box on each side of the top beam and 90 a spring supported in each box and bearing against the pin, as set forth.

7. In an elevator, guide-posts, a car having a top beam, end plates on said beam each having an inclined slot and a wedging projection, 95 and a locking device operated automatically by the breaking of the cable and including levers projecting through the slots and carrying lock-plates sliding on the wedging projections.

8. In an elevator, guide-posts, a car having end plates provided with inclined slots, levers connected to the cable and supported from the car and having their ends projecting through the slots and lock-plates secured to 105 the projecting ends of the levers.

ELIJAH R. VAN ALLEN.
